UNITED STATES PATENT OFFICE.

JULIUS U. FUCHS, OF SEATTLE, WASHINGTON.

BLADE-SHARPENING ATTACHMENT FOR PHONOGRAHS.

1,316,948.

Specification of Letters Patent. Patented Sept. 23, 1919.

Application filed March 10, 1919. Serial No. 281,889.

To all whom it may concern:

Be it known that I, JULIUS U. FUCHS, a citizen of the United States, residing at Seattle, in the county of King and State of Washington, have invented a new and useful Improvement in Blade-Sharpening Attachments for Phonographs, of which the following is a specification.

The primary object of my invention is to utilize the motor-power employed for driving the rotatory table which supports the record-disk in a phonograph, for sharpening blades, and more especially safety-razor blades. To that end my invention is an attachment comprising a pair of stropping or honing members geared together to be rotated on their axes in relatively opposite directions by rotation of the table, and a blade-holder connected with the gearing to be oscillatorily actuated to bear against the opposite edges of a blade held in the holder alternately against the aforesaid members.

In the accompanying drawings, Figure 1 is a broken plan view of a phonograph with my attachment in place thereon; Fig. 2 is a plan view of the attachment with the top-plate of the frame removed to display the gearing and other parts; Fig. 3 is a front end view of the attachment; Fig. 4 is a view in elevation of the supporting leg and top plate of the attachment; and Fig. 5 is a section on line 5—5, Fig. 1, showing the blade-holder and other parts in elevation.

The frame of the device, when constructed as shown, though it may involve any other suitable construction, has a top-plate 7 with a U-shaped leg 8 on one end provided with an 'expanded' base 9. A thumb-screw 10 secures the leg and the plate together and is fastened by a nut 11. A rectangular bracket 12 is secured at one end to the under side of the plate 7 near its rear end and is provided at its opposite forward end with an expanded base 9^a, on a level with the base 9. A shaft 13 is journaled in the base 9^a and bracket 12 and passes through the plate, below which it carries a relatively large friction drive-wheel 14 adapted to be adjusted up and down on the shaft and fastened by a set-screw 15 in its adjusted position. In a relatively small rectangular bracket 16 secured to the under side of the plate near its forward end is journaled a shaft 13^a extending parallel with the shaft 13 and through the plate. These two shafts are geared together by corresponding

toothed wheels 17, 17 secured on them below the plate; and each carries, above the plate, and removably, a cylindrical razor-stropping or razor-honing sharpener 18. 60 The purpose of rendering these members removable, as by withdrawing each lengthwise from its shaft, is to adapt the stropping cylinders to be substituted for the honing cylinders and vice versa. The shaft 13^a 65 carries on its lower end a pinion 19 meshing with a relatively large toothed wheel 20 journaled on the under side of the plate 7 near its center and carrying a semi-circular cam 21 in position to engage the adjacent 70 end of a spring-pressed arm 22 pivoted at its opposite end, at 23, to the under side of the plate near the rear end of the latter. This arm carries between its ends a finger 24 projecting upwardly through an elongated transverse slot 25 in the plate 7.

A shaft 26 rises rigidly from the top of the frame-plate behind and on a line midway between the shafts 13 and 13^a and carries, to be oscillated, a blade-holder 27 80 having a rearwardly-extending tail-piece 28, through an opening in which the finger 24 projects. This holder has a pair of forwardly converging spring jaws 29, 30. A screw 31 projects from the inner face of 85 the jaw 29 through the companion-jaw and carries a thumb-nut 32, by tightening of which a safety-razor blade 33 may be clamped between the jaws in position to cause oscillation of the holder to bear the 90 edges of the blade to be stropped or honed alternately against the sharpeners 18. An adjustable gage 34 is provided on the outer face of the jaw 29 for properly setting the blade in the holder. 95

The operative position of my attachment is on the platform 35 of a phonograph, to which it is secured, at the bases 9 and 9^a, adjacent the rotating table 36 for carrying the record-disks. In that position, when the attachment is out of use the wheel 14 is held by the set-screw in a plane different from that occupied by the record-table. When it is desired to use the attachment, after adjusting in the holder 27 a blade to be sharpened, the wheel 14 is adjusted on the shaft 13 into position to contact its periphery with that of the table 36, driving of which by the phonograph-motor drives the parallel shafts 13 and 13^a in relatively opposite directions, 110 and the gear 20 to rotate the cam 21. In one-half of each revolution of this gear 20

the cam bears against the arm 22 and turns it, in opposition to its spring, in a direction wherein resultant engagement of the finger 24 with the tail-piece 28 turns the blade-holder to bring one edge of the blade to be sharpened against one of the two rolls or sharpeners 18. At the end of that half of the wheel's revolution, the cam clears the end of the arm and its spring throws the 10 blade-holder in the opposite direction to bear the blade-edge against the other sharpening-roll. As will be seen, each throw of the holder causes the respective blade-edge to bear against and be acted upon by the 15 rotating sharpening medium during one-half of the revolution of the gear 20, thus for a sufficient length of time in the stroping or honing operation against each side of the blade-edge.

20 The blade-holder may be readily lifted off its supporting shaft for handling it in removing a sharpened blade and adjusting a blade to be sharpened between the holder-jaws; and it may be as readily returned to 25 its operative position.

I realize that considerable variation is possible in the details of construction thus specifically shown and described, and I do not intend by illustrating a single specific 30 embodiment of my invention to be limited thereto, my intention being in the following claims to claim protection upon all the novelty there may be in my invention as fully as the state of the art will permit.

35 I claim:

1. A blade-sharpening attachment for phonographs, comprising, in combination

with a frame, a pair of rotatable blade-sharpening members geared together to be rotated in relatively opposite directions, a 40 relatively large friction wheel for rotating said members by contact with the revolving table of a phonograph, a blade-holder oscillatorily supported to bear the edges of a blade to be sharpened in the holder alternately against said members, a rotatable cam geared to one of said sharpening members to be driven thereby, and a spring-pressed pivotal arm extending into the path of the cam and having a finger engaging said 45 holder to oscillate it by the cam-action 50 against the arm.

2. A blade-sharpening attachment for phonographs, comprising a frame, means for attaching said frame to the platform of the phonograph, a shaft carried by said frame, a relatively large friction wheel adjustably mounted on said shaft and adapted to be rotated by contact with the revolving table of the phonograph, a rotatable blade-sharpening member carried by said shaft, a second shaft carried by said frame, a rotatable blade-sharpening member carried by said second shaft, gearing connecting said 55 shafts to cause their rotation in opposite directions, a blade-holder carried by the frame, a cam carried by one of said shafts, and a spring-pressed arm extending into the path of the cam to be actuated thereby and connected with said holder to cause it 60 to be oscillated and the edges of the blade carried thereby to alternately contact with 65 said blade-sharpening members.

JULIUS U. FUCHS.
